Azor Blowers

by his Atty Thos. J. Sprague

UNITED STATES PATENT OFFICE.

AZOR BLOWERS, OF CAMBRIDGE, MICHIGAN.

BOLT-CUTTER.

SPECIFICATION forming part of Letters Patent No. 275,015, dated April 3, 1883.

Application filed February 12, 1883. (Model.)

To all whom it may concern:

Be it known that I, AZOR BLOWERS, of Cambridge, in the county of Lenawee and State of Michigan, have invented new and useful 5 Improvements in Bolt-Cutters; and I do hereby declare that the following is a full, clear, and exact description thereof, reference being had to the accompanying drawings, which form a part of this specification.

10 The nature of this invention relates to certain new and useful improvements in the construction of that class of implements which are employed for cutting off wire or other small metallic rods.

15 The invention consists in the peculiar construction of the various parts, and their combinations and operation, as more fully herein-after described.

Figure 1 is a plan view of my improved device with the confining-plate removed. Fig. 2 is a cross-section through the jaws and knives.

In the accompanying drawings, which form a part of this specification, A represents one of the jaws, provided with an ear, a, through 25 which, and a similar ear upon the other jaw, B, a bolt, b, secures the two jaws together pivotally, while the same bolt also passes through the confining-plates C, one being provided for each side of the device. The rear faces of the 30 jaws A B are dovetailed to receive the knives D, having shoulders a' to rest against the inclined sides of the jaws A and B, as shown in Fig. 2, while the front faces are cut away, the chamber E, formed thereby, acting as a guide 35 to facilitate the conducting of the wire to the knives when open. The outer ends of these jaws A B terminate in flat faces e, by means of which the end of the wire may be grasped and twisted, as with a pair of pinchers. A 40 spring, F, is inserted between the arms of said jaws, the function of which is to compel the jaws to remain in an open position except when force is applied. For the purpose of applying this force to the jaws and compelling them to 45 perform the functions designed, I provide two lever-handles, G and H, both of which are pro-

vided with ears d, through which a bolt, e, passes to pivotally secure such lever-handles together, while at the same time the bolt passes through the two confining-plates, and, with 50 the bolt b, firmly holds said confining-plates in place. Each of these handles, at its inner end, terminates in a cam-shaped lug, I, which engages with the circular recesses f upon the inner end of the jaw-arms. J is a stop rigidly 55 secured to one of the confining-plates to limit the travel of the free ends of the lever-handles toward each other to prevent an undue strain upon the cutters or knives.

It is evident from this construction and operation of parts that the jaws provided with the dovetailed cutters may be extended any length to form a pair of shear blades, and such extension of such blades would be within the 60 spirit of the present invention.

65 This implement will be found very useful to those engaged in erecting telegraphic, telephonic, or other wires for electrical purposes, as when constructed as described it furnishes not only the tool for cutting off the wire when 70 desired, but a pair of nippers or pinchers by means of which the end of the wire may be clasped and twisted at pleasure.

What I claim as my invention is—

1. The combination of the jaws A B, spring 75 F, and handles G H with the bolts b e and confining-plates C, the parts being constructed and operating substantially as and for the purposes set forth.

2. In a bolt and rod cutter, the combination 80 of the jaws A B, having plane faces e, spring F, and cutters D D, the latter having shoulders a', and dovetailed, in the jaws, substantially as described, with the confining-plates C, bolts b e, and handles G H, all constructed 85 and operating substantially as and for the purpose set forth.

AZOR BLOWERS.
